UNITED STATES PATENT OFFICE.

GEORGE McCLORY, OF PATERSON, NEW JERSEY.

SANITARY PROTECTING MEANS FOR WATER-CLOSET SEATS.

No. 920,371.

Specification of Letters Patent.

Patented May 4, 1909.

Application filed September 18, 1908. Serial No. 453,662.

To all whom it may concern:

Be it known that I, GEORGE McCLORY, a citizen of the United States, residing in Paterson, Passaic county, New Jersey, have invented certain new and useful Improvements in Sanitary Protecting Means for Water-Closet Seats; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates to water-closets and the like and it has for its object to provide means whereby each person using the closet may avoid direct contact with the seat.

In carrying my invention into practice, I provide a paper or other similar cheap form of sheet-like material wound on a roller, means whereby each person using the closet may advance the material, which is formed with holes coinciding in size substantially to that in the seat, so as to bring a fresh seat-face over the seat and means for mutilating the paper and for thereupon turning it into the bowl of the closet so that it will pass out in the flushing thereof.

My invention will be found fully illustrated in the accompanying drawings, wherein:

Figure 1 is a view in front elevation, partly in section, of a water closet and the apparatus constituting my invention; Fig. 2 is a side view of the upper part of the apparatus, looking from the left in Fig. 1; Fig. 3 is a plan view of what is shown in Fig. 2, certain parts being removed; Fig. 4 illustrates a detail; and, Fig. 5 shows the preferred form of the paper strip which I employ.

a designates the bowl of the water-closet and *b* its hinged seat, the latter preferably having in the present instance its under side cut away, as at *c*, to form an opening whose purpose will hereinafter appear more clearly.

To the floor at, preferably, the right side of the bowl (as one faces the latter) are bolted the lower members *d* of the vertically adjustable uprights *e*, the upper members *f* of which are formed with slots *g* receiving bolts *h* in the members *d*. The upper members *f* are formed with the enlargements *i* which may be connected together by the braces *j* and afford bearings for the trunnions of upper coacting rollers *k*, having rubber faces

and arranged in a horizontal plane, the guide roller *l*, arranged between rollers *k* and the closet, and the lower or mutilating rollers *m*, arranged in a horizontal plane beneath rollers *k* and provided with the radial teeth *n* adapted to coact in mutilating or shredding a sheet of paper or the like passed between them; brackets *o* are attached to the uprights and in these is journaled another guide roller *p* which lies close to but not quite in contact with the seat, screws *q* being preferably employed to secure said brackets to the uprights so that when necessary the roller and brackets may be removed.

The rollers *k* carry at their rear ends intermeshing pinions *k'* and the front trunnion *r* of the left-hand roller *k* in Fig. 1 carries a crank *s* and a gear *t*, the latter meshing with an idler pinion *u* journaled on a stub-shaft *v* projecting from the adjoining upright. Said pinion in turn meshes with another pinion *w* on the other trunnion of one of the rollers *m* which pinion (*w*) itself meshes with a pinion *x* on the trunnion of the other roller *m*, said pinion *x* being slightly larger than pinion *w* so that different surface speeds will be attained in the rollers *m* for the purpose of increasing the mutilating action thereof.

A paper guide *y*, arranged with its upper end in opposite relation to the line of contact between rollers *k* and its lower end in similar relation to the rollers *m*, is secured to the uprights (see Fig. 2 and dotted outline in Fig. 1). Another paper guide *z*, having its lower discharge end constructed in width and turned off toward the bowl *a* in a gradual curve, is also secured to the uprights, its contracted end being normally received in the opening *c* in the seat.

The paper strip *1* is shown in Fig. 5 and is formed with the openings *2*, each having the slits *3* at the front so that it will take the curve of the front surface in the opening of the seat *b* without breaking when pressed against the same by a person seated upon it. Further, to prevent unduly tearing the paper along its front edge by the pressure of the legs of the person seated upon it, said front edge is scalloped to form leg-recesses *4*.

The paper strip is taken from a roll *5* journaled in a suitable bracket *6* at the left of the bowl, said bracket comprising members *7* and *8* vertically adjustable by virtue of slot and bolt connections *9* between them, the upper member carrying a guide roller *10* whose top is about on a level with the top

surface of the seat. The paper strip runs from the supply roll 5 over guide roller 10, across the seat, under guide roller p, over guide roller l; down between the rollers k, 5 which serve to feed it, through guide y, between the mutilating rollers m, where it is shredded or otherwise mutilated, and then entering the bowl through the guide z. Being mutilated, it will be understood that the 10 paper will not tend to clog the closet.

In order to insure the paper clearing the 15 guide z I prefer to provide means for directing an air-blast therethrough and to this end provide a pump 11 which is attached to one 20 of the uprights e and has its nozzle formed as a pipe 12 which extends parallel with the guide z horizontally and has discharge tubes 13 projecting therefrom into the upper end of said guide, the piston rod 14 of the pump being 25 pivotally connected with one end of a lever 15 fulcrumed in said upright and having its other end pivotally connected with a pitman 16 in turn connected with a pin 17 on a face-plate 18 on the trunnion of the left-hand roller m in Fig. 1. Thus, as the crank 30 is turned to effect the advance of the paper over the seat, the pump causes blasts of air to be discharged down through the guide z and clear its passage of the shreds or pieces of paper therein.

I do not wish to be limited to the several 35 details of construction described and shown herein, what I claim being:

1. The combination, with a closet and its 40 seat, of means for guiding an apertured strip over the top surface of the seat, means for advancing the strip, and a strip guide, coöperating with the advancing means, and discharging into the closet, substantially as described.

2. The combination, with a closet and its 45 seat, of means for guiding an apertured strip over the top surface of the seat, means for advancing the strip, said means comprising coacting rollers, and a strip guide discharging into the closet and having its receiving end opposite the inter-contacting portions of said rollers, substantially as described.

3. The combination, with a closet and its

seat, of means for guiding an apertured strip 50 over the top surface of the seat, means for drawing the strip over the seat and for simultaneously mutilating the used portion thereof, and means, disposed between the second 55 means and the closet, for directing the mutilated strip into the closet substantially as described.

4. The combination, with a closet and its seat, of means for guiding an apertured strip over the top surface of the seat, means for 60 advancing the strip comprising mutilating rollers, and means, disposed between the second means and the closet, for directing the mutilated strip into the closet substantially as described.

5. The combination, with a closet and its seat, of means for guiding an apertured strip over the top surface of the seat, means for drawing the strip over the seat comprising 70 mutilating rollers, and a guide for the mutilated portion of the strip arranged relatively between the rollers and the closet and discharging into the latter, substantially as described.

6. The combination, with a closet and its 75 seat, of means for guiding an apertured strip over the top surface of the seat, means for drawing the strip over the seat and for simultaneously mutilating it, and means for directing a blast against the mutilated portion 80 of the strip and into the closet, substantially as described.

7. The combination, with a closet and its seat, of means for guiding an apertured strip over the top surface of the seat, means for 85 drawing the strip over the seat and for simultaneously mutilating it, a guide for receiving the mutilated portion of the strip discharging into the closet, and means for directing an air-blast through said guide, substantially as 90 described.

In testimony, that I claim the foregoing, I have hereunto set my hand this 17th day of September, 1908.

GEORGE McCLORY.
